(57) **CLAIM**

We claim the ornamental design for a packaging pump container, as shown and described.

DESCRIPTION

FIG. 1 is a perspective view of a packaging pump container, showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a right side view thereof showing a configuration of use in which an inner cap is shown in a closed position. The broken lines in the drawings show portions of the packaging pump container that form no part of the claimed design.
